UNITED STATES PATENT OFFICE

146,704

DESIGN FOR A COMBINED SOUND MOTION PICTURE PROJECTOR, AMPLIFIER, AND LOUDSPEAKER

Guillermo A. del Valle, Merchantville, N. J., assignor to Radio Corporation of America, a corporation of Delaware

Application August 10, 1946, Serial No. 132,425

Term of patent 14 years

(Cl. D61—1)

To all whom it may concern:

Be it known that I, Guillermo A. del Valle, a citizen of the United States and a resident of Merchantville, in the county of Camden and the State of New Jersey, have invented a new, original, and ornamental Design for a Combined Sound Motion Picture Projector, Amplifier, and Loudspeaker, of which the following is a specification, reference being had to the accompanying drawings, forming a part thereof.

Figure 1 is a perspective view of a combined sound motion picture projector, amplifier, and loudspeaker, showing my new design; and

The dominant features of my design reside in the portions shown by means of full lines in the drawings.

I claim:

The ornamental design for a combined sound motion picture projector, amplifier, and loudspeaker, substantially as shown and described.

GUILLERMO A. DEL VALLE.
